UNITED STATES PATENT OFFICE.

RALEIGH J. HIMMELRIGHT, OF INDIANAPOLIS, INDIANA.

MECHANICAL STOKING APPARATUS.

1,173,270.

Specification of Letters Patent. Patented Feb. 29, 1916.

Application filed December 5, 1913. Serial No. 804,881.

To all whom it may concern:

Be it known that I, RALEIGH J. HIMMELRIGHT, a citizen of the United States, residing at Indianapolis, Marion county, and 5 State of Indiana, have invented and discovered certain new and useful Improvements in Mechanical Stoking Apparatus, of which the following is a specification.

My invention relates to mechanical stoking apparatus for locomotives and its object is to provide means whereby the fuel may be distributed in such manner as to obtain a thorough combustion of the entire body thereof fed to the fire box and thus a 15 more effective utilization of the heat energy obtained than has been possible in practice with devices of the same class.

To this end my invention is embodied in preferable form in the construction and arrangement hereinafter described and illustrated in the accompanying drawings.

In these drawings, Figure 1 is a plan view of a part of a locomotive tender and a part of a locomotive, particularly showing the 25 fire box; Fig. 2, a side view in elevation of the same parts; Fig. 3, an enlarged rear end view of the fire box conveyer operating mechanism taken on the section line 3—3 of Fig. 2; Fig. 4, an enlarged section on the 30 line 4—4 of Fig. 1; Fig. 5, an enlarged detail section of the conveyer trough section leading from the tender and the connecting section; Fig. 6, a cross section on the line 6—6 of Fig. 5; Fig. 7, an enlarged detail 35 section on line 7—7 of Fig. 2; Fig. 8, an enlarged detail plan view of the valve operating cam drum; Fig. 9, an elevation of said cam drum; Fig. 10, a section on line 10—10 of Fig. 9; Fig. 11, a detail section 40 on lines 11—11 of Figs. 10 and 12; Fig. 12, a detail section on line 12—12 of Fig. 11; Fig. 13, a detail of a modified form of cam and Fig. 14 a detail section on line 14—14 of Fig. 13.

45 Referring to the drawings, 1 indicates the tank of a locomotive. Mounted within this tank is a fuel receiving box 2, which is adapted to be closed at its upper part by sliding doors 3. These doors are provided 50 with holes 4 which are adapted to be engaged by a suitable hooked rod which is operated by the fireman to open or close the sliding doors. The coal is piled in the tender above the box 2 and when any of the 55 doors is opened the coal will fall into the box. Extending through this box is a spiral

screw conveyer 5. The box is prolonged in a trough or casing 6 which extends forwardly from the tank or tender under the cab floor of the locomotive. This trough communicates with another trough section 7 extending angularly and outwardly from the first trough and in the trough section 7 is mounted another section 8 of a spiral screw conveyer. The section 7 at its inner end adjacent to section 6 is lower than the latter section whereby it is adapted to receive by gravity the coal fed from trough 6.

The trough section 7 communicates at its outer end at 9 with a trough section 10. In 70 the trough section 10, is mounted another section 11 of a spiral screw conveyer which extends forwardly parallel to the side of the fire box to a point adjacent the front wall of the fire box. The conveyer section 8 and 75 the section 11 are connected at the junction 9 of their respective troughs by a universal joint coupling 12. The shaft 13 of the conveyer section 11 is provided at its forward end with a gear 14 which is adapted to mesh 80 with a gear 15 carried by a driving shaft 16 which is provided intermediate its ends with a universal joint 17. The rear end of this driving shaft is provided with a worm wheel 18 which is driven by a worm 19 85 mounted on a shaft 20 of a change speed engine 21 suitably mounted on the locomotive, preferably below the body thereof but having suitable means of control, extending into the locomotive cab. The gear connections above described serve for driving the conveyer section 11 and the speed at which this conveyer is driven may be altered as described by changing the speed of the engine. 90

Carried by the shaft 16 near the rear end 95 thereof is a gear wheel 22, which is connected by a chain 23 with a gear wheel 24 on the extended shaft 25 of the first conveyer section 5, whereby said section 5 is rotatably driven synchronously with the 100 other two sections of the conveyer.

The two trough sections 7 and 10 are preferably connected by means of a pin 26 which provides a flexible joint between these sections which serves to permit the 105 trough to yield to the action of the conveyer and thus prevent a binding action thereof.

The coal used is slack or broken pieces of a size running up to dimensions capable of forcing through a two and one-half inch 110 screen mesh. This coal is adapted to be fed forward from the box in the tank by the

conveyer to the point of delivery in the fire box. This point of delivery in my invention is located substantially at the front wall of the fire box and it is the design of the invention to distribute the coal rearwardly from this front wall over the grate surface, and under and from the base of the deflecting or baffle arch, which extends from the front part of the fire box upwardly and rearwardly over a portion of the grate.

The trough containing the conveyer is turned at an angle at its forward end and enters the fire box and leads to a substantially flat horizontal coal receiving plate 27 mounted preferably in one corner of the fire box at the forward end thereof. This plate is located above the level of the grate 28 and below a deflecting and baffle arch 29, which is supported by an arch tube 30 extending from wall to wall of the fire box. This arch is made of fire brick and is of the form customarily employed in mechanical locomotive stokers and serves to deflect the flames and products of combustion toward the rear of the fire box and to prevent the fuel from being carried immediately toward the flues by the draft through the grate, so as to thereby retain the fuel in the fire box until it has been properly burned and to confine the flames to the grate area to effect this combustion so that all of the heat energy of the fuel will be effectively utilized.

Projecting upwardly through the bottom of the fire box and through the plate 27 are jet pipes 31, 32 and 33, which terminate in suitable nozzles and are adapted to receive steam from a suitable source of supply such as the main boiler, and to project jets of steam across the surface of the plate immediately adjacent the opening from the conveyer, so as to thereby distribute the coal deposited by the conveyer on the plate over the area of the fire box. These steam jets are preferably three in number and they are so disposed as to project the coal in different streams having different directions, within the fire box. Thus the jet 31 is adapted to direct the coal substantially in the direction indicated by the lines 34, that is toward the rear of the fire box, but in a line closely following the side of said fire box. The jet of pipe 32 is adapted to direct the fuel distributed thereby substantially in the lines indicated at 35, and is, substantially over the center of the grate, while the jet 33 is adapted to distribute the coal in the lines 36.

The pipes connecting with the steam jet nozzles are adapted to be controlled by valves interposed in the lines of such pipes and which valves are adapted to be automatically and intermittently operated in succession by mechanism located in the locomotive cab. These valves are designated by the reference characters 37, 38 and 39 corresponding respectively to the steam jet

nozzles of the pipes 31, 32 and 33. The rods of these valves are adapted to be automatically operated by means of separate rows of cams mounted on a rotary cam drum 40. This cam drum is adapted to be driven by a belt 41 connecting a gear on the shaft of the drum with a gear on the drive shaft 16. The cams for the respective controlling valves are mounted in rows transversely spaced apart on the surface of the drum and the respective rows corresponding to the above valves are designated by the numerals 42, 43 and 44. It will be seen that owing to the series of cams for each valve, said valve is adapted to be operated intermittently. The cams of the different rows are also staggered with respect to the cams of the adjoining rows whereby the operation of the respective valves will also be successive. By this arrangement, one of the steam jet nozzles, as for instance, the nozzle of pipe 31, will be first operated by one of the cams in the row 42 to project a body of fuel across the grate and into the fire box and this nozzle will then be cut off by the rotation of the cam drum and then the next nozzle 32 will be operated by a cam of the adjoining row and then the latter nozzle will be closed and then the third nozzle will be opened, so as to project the fuel therefrom and this operation will be continued by the automatic action of the drum, the jet nozzles being successively and intermittently opened and intermittent and successive streams of fuel in different directions being driven over the surface of the grate.

The cams are so mounted on the drum as to be capable of being adjusted out of the line of their respective valve rods, in order that the intervals between the operations of the valves may be changed or one of the valves cut out of operation altogether. To this end, as shown in Figs. 10 to 12 inclusive, each cam is adapted to project through an enlarged slot 45, whereby it is permitted to be turned down out of the path of the roller on the end of the valve rod. Each cam is mounted on a slideable shaft 46, which has a squared head 47, adapted to be slid into and out of a squared socket in the wall of the drum in order to lock the rod against turning or make it free to be turned for adjusting the cam. A spring 48 serves to normally hold the cam shaft outwardly in locked position.

In Figs. 13 and 14, a modified form of adjustable cam is shown in which the cam 49 is adapted to be slid in and out by means of a sliding rod 50. A globe valve 51 is interposed in each of the pipe lines 31, 32 and 33 whereby the steam from the boiler through the lines may be entirely cut off or regulated as desired.

In the operation of the device, the stoker or fireman will open the sliding doors in the box 2, admitting fuel to the conveyer which

carries the same to the front part of the firebox and thereupon the steam jet nozzles operate to distribute the fuel over the grate surface in different streams intermittently 5 and successively, as above described.

The advantage of distributing the fuel from the front end of the fire box and from a point underneath the baffle arch is that the fuel must travel substantially the entire 10 length of the grate and in so doing must pass over the burning bed of fuel on the grate and will fall upon the grate surface and be consumed thus avoiding the danger of part of the coal being carried upwardly 15 between the rear end of the box and the arch by the strong draft without being burned, as in those constructions in which the fuel is fed into the fire box at the rear end thereof.

20 Having thus described my invention, what I claim is:—

1. In mechanical stoking apparatus, in combination with a locomotive fire box, coal containing means, mechanical apparatus for 25 conveying the coal from said containing means to a point at the front end of the fire box, means for receiving the coal thereat, and blasting means discharging at said receiving point for distributing the coal 30 throughout the fire box, substantially as described.

2. In mechanical stoking apparatus for locomotives, in combination with a fire box, coal containing means, mechanical apparatus 35 for conveying the coal from said containing means to a point on one side and at the front end of the fire box, means for receiving the coal thereat, and a plurality of jets operable to discharge blasts in different 40 directions from said receiving point for distributing the coal throughout the fire box, substantially as described.

3. In mechanical stoking apparatus for locomotives, in combination with a fire box, 45 coal containing means, mechanical coal con-

veying means leading from said containing means to the front end of the fire box, a baffle arch leading into the furnace rearwardly from the front end of the fire box above the grate, means for receiving the coal 50 beneath and adjacent the base of said arch, devices for directing blasts in different directions for distributing the coal throughout the fire box, and controlling means for said blasts located at the rear end of the 55 fire box, substantially as described.

4. In a mechanical stoking apparatus, in combination with a fire box, means for feeding fuel thereto, a series of jet nozzles for distributing the fuel into the fire box, controlling valves for said nozzles, a source of gaseous fuel for said jet nozzles, a rotary drum, a series of cams on said rotary drum operable to actuate said valves, said cams being staggered whereby said valves are 60 adapted to be operated successively, and means for adjusting said cams, substantially as described.

5. In mechanical stoking apparatus for locomotives, in combination with a fire box, 70 coal containing means, coal conveying means leading from said containing means to the front end of the fire box, a baffle arch leading into the furnace rearwardly from the front end of the fire box above the grate, 75 means for receiving the coal mounted below said arch adjacent the base thereof, separate mechanisms for distributing the fuel throughout the fire box in different directions and means for successively and intermittently operating said mechanisms, 80 substantially as described.

In witness whereof, I have hereunto set my hand and seal at Indianapolis, Indiana, this third day of December, A. D. nineteen 85 hundred and thirteen.
